T. SCHULZ.
STAPLE PULLER.
APPLICATION FILED APR. 22, 1916.

1,193,930.

Patented Aug. 8, 1916.

Inventor

THEODOR SCHULZ

By Watson E. Coleman

Attorney

UNITED STATES PATENT OFFICE.

THEODOR SCHULZ, OF OLIVET, SOUTH DAKOTA.

STAPLE-PULLER.

1,193,930.

Specification of Letters Patent. Patented Aug. 8, 1916.

Application filed April 22, 1916. Serial No. 92,979.

To all whom it may concern:

Be it known that I, THEODOR SCHULZ, a citizen of the United States, residing at Olivet, in the county of Hutchinson and State of South Dakota, have invented certain new and useful Improvements in Staple-Pullers, of which the following is a specification, reference being had to the accompanying drawings.

10 This invention relates to certain improvements in staple pullers and it is an object of the invention to provide a device of this general character wherein are employed two relatively movable pivoted jaws adapted to effectively engage a staple, and serve as a fulcrum whereby the requisite strain may be imposed upon the staple to assure its extraction.

20 The invention consists in the details of construction and in the combination and arrangement of the several parts of my improved staple puller whereby certain important advantages are attained and the device is rendered simpler, less expensive and 25 otherwise more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings, wherein—

Figure 1 is an elevational view illustrating a staple puller constructed in accordance with an embodiment of my invention; and Fig. 2 is a fragmentary elevational view of the plate as herein embodied, and illustrating certain details of construction.

40 As disclosed in the accompanying drawings, 1 denotes a plate substantially oval in form and having its outer end provided with the transversely disposed recess 2. Arranged adjacent the forward end of the plate 45 and substantially at opposite sides of the recess 2, are the pins 3 having pivotally engaged therewith the jaws 4 extending beyond the outer end of the plate and curved inwardly so that when said jaws are operatively disposed through a staple, either of 50 said jaws will serve as a fulcrum, whereby the requisite strain may be imposed upon the staple to assure its extraction.

The jaws 4 are provided with the rearwardly disposed extensions 5 with which coacts the cam member 6 pivotally supported

by the pin 6a adjacent the rear end of the plate 1, and as herein embodied, said cam includes a substantially inwardly and transversely disposed rounded extension 7 which 60 coacts with the cam edge 8 formed on the inner end of one of the extensions 5, and is also provided with a substantially forward and longitudinally disposed extension 9 adapted to coact with the inner end of the 65 extension 5 of the second jaw 4, whereby it will be perceived that upon the cam member 6 being rotated in one direction, the extensions 5 will be moved in unison in opposite directions and thereby resulting in an inward relative movement of the jaws 4, whereby the same may be effectively forced through a staple.

As herein disclosed, the cam 6 is provided with a rearwardly disposed operating handle 75 or lever 10 coacting with the stationary handle or lever 11 carried by the plate 1, whereby it will be readily perceived that the device may be operated by a hand of the user. The extensions 5 of the jaws 4 are 80 maintained constantly in contact with the cam member 6 through the medium of the retractile member 12 interposed between the extensions 5 at a point intermediate the pivotal mountings of the jaws 4 and the cam 6, 85 said retractile member being herein disclosed as a conventional coil spring having its extremities suitably engaged with the extensions 5.

In order that the jaws 4 may be maintained normally in separated relation, I provide the stationary handle or lever 11 with the flat spring 14 which coacts with the handle or lever 10 of the cam 6, whereby said handles or levers 10 and 11 are normally maintained in separated relation. I also find it of advantage to provide the outer edge of the cam 6 with a notch 15 coacting with a notch 16 suitably produced in the periphery of the plate 1, whereby the device 95 may be employed with facility and convenience as a wire cutter.

From the foregoing description, it is thought to be obvious that a staple puller constructed in accordance with my invention 105 is of an extremely simple and comparatively inexpensive nature and is particularly well adapted for use by reason of the convenience and facility with which it may be assembled, and it will also be obvious that my invention 110 is susceptible of some change and modification without material departure

from the principles and spirit thereof and for this reason I do not wish to be understood as limiting myself to the precise arrangement and formation of the several parts herein shown in carrying out my invention in practice.

I claim:

A staple puller comprising a plate, coacting jaws pivotally supported by the plate and extending beyond an end thereof, said jaws being curved one toward the other, the end of the plate intermediate of the jaws being recessed, inwardly disposed extensions carried by the jaws, one of said extensions being of a greater length than the extension of the second jaw, a cam member pivotally supported by the plate at a point rearwardly of the jaw provided with the short extension, said cam being provided with a substantially transversely disposed extension

and coacting with the outer end portion of the longer extension, the outer contacting edge portion of said extension being of cam formation, and a substantially longitudinally disposed extension coacting with the inner edge of the short extension, a retractile member interposed between and connected to the extensions of the jaws for maintaining said extensions in contact with the cam, a stationary handle carried by the plate, a handle carried by the cam and coacting with the first named handle and a spring interposed between the handles for normally maintaining the same in spaced relation.

In testimony whereof I hereunto affix my signature in the presence of two witnesses.

THEODOR SCHULZ.

Witnesses:

ANNA S. WALTER,
ALVINA GUENTHNER.
